TELEPHONE SYSTEM

Walter Mai, Berlin-Siemensstadt, and Herbert Richter, Berlin-Charlottenburg, Germany, assignors to Fides Gesellschaft fur die Verwaltung und Verwertung von gewerblichen Schutzrechten mit beschränkter Haftung, Berlin, Germany, a corporation of Germany

Application September 16, 1939, Serial No. 295,242
In Germany September 27, 1938

5 Claims. (Cl. 179—18)

The present invention relates to a relay selector which on the coming into effect of a call impulse connects an incoming line with a free outgoing line.

Arrangements are known in which when a call is made the busy condition of all lines outgoing over the relay selector is determined simultaneously and in which further, all free outgoing lines are, at the same time, prepared for seizing. Since the outgoing lines are multiplied to the contacts of a plurality of relay selectors the danger arises that a number of incoming lines may be connected to one and the same outgoing line when simultaneous call impulses are effective on a number of relay selectors and the busy condition of the outgoing lines at these relay selectors is determined at the same time. The object of the present invention is to prevent the undesired interconnection of a number of incoming lines using the simplest means and producing completely positive operation. The object is attained in that all test relays which on the coming into effect of a call impulse determine the engaged condition of the lines outgoing over the relay selectors, are controlled by two contact chains, of which one determines the series succession in which the outgoing lines can be seized, while the second chain determines the series succession in which the various relay selectors are to have access to the same outgoing line.

In the drawings an embodiment of the invention is shown. Figs. 1 and 2 taken together, with Fig. 2 on the right of Fig. 1, show three relay selectors for connecting with idle outgoing trunk lines VL1, VL2 and VL3. The selector MWa is shown in full, while selectors MWb and MWc are shown in part. All circuit details not completely necessary for the understanding of the invention, as well as the circuit of the connecting arrangements lying on either side of the relay selectors in the connecting path, are omitted.

At a connecting arrangement previous to the relay selector MWa positive potential is connected to the seizing conductor 1 and thus the circuit for the seizing relay Ca is completed. Relay Ca at its contacts 3ca connects the slow-to-operate relay Ca1 to the seizing conductor 1. Further over contacts 4ca to 7ca it connects negative potential to the high resistance windings 1 of relays Da1, Da2, Da3, etc. The relays Da are the test relays which determine the condition of the outgoing lines accessible over the relay selector MWa of which three lines VL1 to VL3 are shown.

If all three lines are free then the associated relay Da of the relay selector MWa operates but not the seizing relays C11, C12, C13. Only the relay Da1 can maintain its armature attracted and hold its contact da1 in the operated condition since it opens contact 8da1 in the contact chain consisting of the contacts of all the test relays of the relay selector, and thus interrupts the energising circuit over the energising winding of the relays Da2, Da3, etc. associated with the other lines VL2, VL3.

If the junction VL1 is engaged then the contact 9c11 controlled by its seizing relay C11 is opened and the relay Da1 can accordingly not operate, and the relay Da2 which tests the condition of the junction VL2 can operate if the line is free, and at contact 10da2 open the energising circuit for the test relay Da3 arranged further along the line so that no test relay of another free outgoing line can remain energised.

The contact chain which in addition to the contacts 5ca, 6ca etc. consists of the contacts 8da1, 10da2, 11da3, etc. of the test relays of the relay selector determines the series succession in which the outgoing lines accessible over the relay selector can be seized.

It is assumed that the junction VL1 is free and accordingly relay Da1 is energised. At contact 12da1 it connects its holding winding II and at contact 13da1 opens the holding circuit of the next test relay which has determined the free condition of the junction which it tests. Accordingly if this test relay, for example Da2, although its energising circuit has been interrupted at contact 8da1, has already closed its contact 14da2 and opened contact 15da2 it cannot maintain its armature attracted since the holding circuit is opened at contact 13da1.

Over the holding winding of the test relays the seizing impulses are transmitted to the individual outgoing lines. In order not to seize all the free junction lines at the same time the seizing impulse in the relay selector MWa is only transmitted to the associated junction after a delay. This result is obtained due to the delayed operation of the auxiliary relay Ca1 connected by the seizing relay Ca. The delaying operation is so arranged that the contacts of the relay are only operated when the testing operation is completed and when it has been determined which of the outgoing lines is to be used for the connection to be set up by means of the contact chain which controls the energising circuit of the test relays.

55 The provision of the junction arrangements

on either side of the relay selector determine whether a special common switching through relay is necessary or not. In many cases it is sufficient to provide a switching through stage in each of the access means branching from the incoming line to the individual outgoing line. This switching stage, e. g. contacts 16da1, 17da1 in the access means to the line VL1, is closed by the test relay Da1 before the seizing relay C1 of the outgoing line operates, since the seizing impulse, as already mentioned, is only transmitted to this line after a delay. When a switching through stage is sufficient in each of the individual access means, the special switching through relay Pa shown in the drawings is not necessary. Positive potential is then connected directly over contacts 18ca1 and the junction points 19, 20 to the first contact of a contact chain controlling the holding circuit of the test relays, and effects the energising of the seizing relay C11 in the circuit: +, contact 18ca1, junction points 19, 20, contact 12da1, winding II of relay Da1, relay C11, -. The conductors serving for trunk calls are then switched through metallically as is indicated by the dotted lines.

When all outgoing lines in this arrangement are engaged, a buzzer is connected to the upper conductor serving for interexchange traffic over the series contacts 21da1, 22da2, 23da3, 24ca1, as an engaged signal for the calling station. At the same time positive potential is connected over the contacts 25da1, 26da2, 27da3 and the resistance 28 to the lower conductor.

When, however, switching through to the selected outgoing line e. g. VL1, must not occur before the energising of the seizing relay of this line, i. e. before the energising of relay C11, a special switching through relay Pa is provided.

On the first contact of the contact chain which controls the holding circuit for the test relays positive potential is connected over contact 29ca1, the relay Pa and junction points 30, 20. In the two conductors serving for interexchange traffic, switching through contacts 31pa and 32pa are then provided. If all outgoing lines are engaged none of the test relays Da is energised. The energising circuit for the switching through relay Pa is not completed. The engaged signal is connected over contact 33pa to the upper conductor and + over resistance 34 and contact 35pa to the lower conductor.

Relay Ca1 which transmits the delayed seizing impulse to the selected outgoing line on its operation, disconnects the seizing relay Ca by opening contact 2ca1 and over contact 36ca1 locks up in a circuit extending over the seizing conductor 1. Relay Ca restores and opens contacts 4ca, 5ca, etc. in the contact chain which controls the energising circuits of the test relays.

Relay C11 operating on the coming into effect of the seizing impulse on the junction line VL1 being taken into use, opens contact 9c11 and thus disconnects idle potential (+) from the test conductor.

The case will now be considered in which all junctions VL1, VL2, VL3 are free and calling impulses are transmitted simultaneously by all three relay selectors MWa, MWb, MWc. In addition to the relays Ca in the relay selector MWa1 the relays Cb and Cc not shown of the discriminating selectors MWb and MWc are also energised. Simultaneously with contacts 4ca to 7ca the contacts 37cb, 38cb, 39cb, 40cb are closed in the energising circuits of the test relay Db of the relay selector MWb, and the contacts 41cc, 42cc, 75

43cc and 44cc in the relay selector MWc. Since all three junctions are free the three test relays in each discriminating selector are energised.

The connecting together of a number of incoming lines in such a manner that the same outgoing line is seized at the associated relay selectors is now prevented by the provision of further contact chains controlling the test relays of the selector. Each contact chain has as its object the determination of the series succession in which the individual relay selectors will have access to one and the same outgoing line. Accordingly a contact chain is provided for each outgoing line which consists of contacts of those test relays of the associated discriminating selector which determine its seized condition. Thus the contact chain preventing a multiple seizing of the outgoing line VL1 consists of contacts 45da1, 46db1, 47dc1; the contact chain which prevents the multiple seizing of the line VL2 consists of contacts 48da2, 49db2, 50dc2 and the contact chain which prevents the multiple seizing of the line VL3 consists of contacts 51da3, 52db3, 53dc3.

When the line VL1 is free, all three discriminating selectors MWa, MWb and MWc have their test relays operated. Relay Da1 at contact 45da1 disconnects positive potential from the energising winding I of relay Db1 which closes contact 46db1 again should this already have been opened. Also the relay Dc1 cannot operate since positive potential is connected at contact 45da1.

At the discriminating selector MWb accordingly, contact 54db1 is closed again should this already have been opened. Relay Db2 operates and by opening contact 49db2 prevents an energising of relay Dc2. The incoming line with which the discriminating selector is associated is thus connected with the outgoing line VL2.

In the discriminating selector MWc since the contacts 55dc1 and 56dc2 are closed the test relay Dc3 operates. This discriminating selector thereby connects its incoming line with the outgoing line VL3.

We claim:

1. In a relay selecting switch having means for connecting any one of a plurality of incoming lines to an idle one of a plurality of outgoing lines, a plurality of test relays for each incoming line one for each outgoing line, a contact chain controlled by said relays and operated upon initiation of a call from one of said incoming lines to determine the series succession in which the outgoing lines may be seized and another contact chain controlled by said relays for determining the succession in which said selectors have access to the same outgoing line.

2. A relay selector such as claimed in claim 1 in which the first chain includes a contact set on all the test relays of an incoming line, and the second chain includes contacts on corresponding test relays of each incoming line.

3. In a relay selector, an incoming line, a plurality of outgoing lines accessible thereto, a plurality of test relays individual to the incoming line one for each outgoing line, means for making certain of the outgoing lines busy, means responsive to the initiation of a call over said incoming line for completing circuits over all test relays associated with idle trunks, a chain of contacts controlled by said relays and operated when the relays are energized to open the circuits of all but one of said relays and to complete a locking circuit for that one relay, said chain of contacts arranged to insure a definite order of success-

sion in which the idle outgoing lines may be seized.

4. A relay selecting system such as claimed in claim 1 in which there are holding circuits for each test relay, and a third chain of contacts controlled by said relays for controlling said holding circuits.

5. In a relay selecting system, a plurality of incoming lines, a relay selector for each line, a plurality of trunk lines accessible in common to said selectors, a series of test relays for each selector one for each trunk line, a chain circuit for

all relays of one selector for providing a definite order of access by that selector of the trunk lines, a chain circuit for the relays of all selectors corresponding to the same trunk line for providing a definite order of access of the selectors to that trunk line, and means responsive to the initiation of each call over an incoming line for completing a circuit for each test relay associated with an idle trunk line.
